UNITED STATES PATENT OFFICE.

STEPHEN ANDRÉ BRANDON, OF LEIPSIC, GERMANY, ASSIGNOR TO
DOUGLAS HORACE BRANDON, OF PARIS, FRANCE.

OVERSEAMING SEWING-MACHINE.

SPECIFICATION forming part of Letters Patent No. 650,297, dated May 22, 1900.

Application filed December 28, 1898. Serial No. 700,537. (No model.)

To all whom it may concern:

Be it known that I, STEPHEN ANDRÉ BRANDON, mechanical engineer, a subject of the Queen of Great Britain, residing at Leipsic, 5 in the Empire of Germany, have invented certain new and useful Improvements in Machines for Overseaming Fabrics; and I do hereby declare that the following is a full, clear, and exact specification of the same.

10 This invention has relation to sewing-machines adapted generally for producing felled seams, and particularly for sewing cut knitted goods or hosiery.

As is well known, the cut edges of knitted 15 goods curl or roll up, rendering it difficult to hem such goods, and prior to my invention it has been proposed to overcome this difficulty by combining with suitable stitch-forming appliances a suitable hemmer and appliances 20 for uncurling the edges of the goods before said edges are folded over and presented to the stitch-forming appliances.

My invention has for its object a construction of sewing-machine whereby the 25 described appliances are dispensed with, but which is simple in so far as its operative mechanism is concerned, not more liable to get out of repair than any ordinary sewing-machine, and whereby flat and pliable simple 30 felled seams, or what is known as the "French felled seam" may be produced.

Referring to the accompanying drawings, Figures 1 and 3 are side elevations, partly in 35 section and showing the stitch-forming appliances in different positions; and Fig. 2 is an end elevation of a sewing-machine embodying my invention. Fig. 4 is a detail side 40 elevation illustrating more clearly the presser-foot, the work or needle plate, and the guide for the felling-needle, the parts being shown in their respective positions illustrated in Fig. 3. Fig. 5 is a plan view, partly in section, of the parts shown in Fig. 4; and Figs. 6, 6^a, 7, 8, and 9 are seam-sections on a larger 45 scale, Fig. 6 illustrating the manner in which the sewing is done in existing two-needle machines for producing a double or French felled seam in one operation applied to woven materials only, Fig. 6^a illustrating the manner 50 in which sewing is done generally in the case of knit goods, Fig. 7 illustrating the manner

in which a French felled seam is produced on my improved machine, Fig. 8 showing the material unfolded after removal from the machine, and Fig. 9 illustrating a simple felled 55 seam also produced on my improved machine by dispensing with one of the needles.

Referring to Figs. 1, 2, and 3, A indicates the frame of the machine, which may be of any desired and suitable shape and construction 60 for carrying the operating parts.

a is the bed-plate, and a' is the needle or work plate.

B is the driving-shaft, which is suitably carried in the lower part of the frame A underneath the bed-plate a, and carries at its outer end the usual driving-pulley b. This shaft B carries a spherical eccentric b' next to the pulley b and which works in an eccentric-strap c of corresponding shape formed 70 on the lower end of a connecting-rod C, the upper end of which is formed by a second strap c', that embraces a ball D. This ball is connected by means of a screw-threaded tail-piece d and of a lock-nut d' to a bent or 75 bell-crank lever E for operating the needle-bars. This lever is keyed on a conical axle e, which is journaled in any suitable manner on the frame A of the machine, and it is oscillated from shaft B through the mechanism 80 above described—namely, the eccentric b', ball-bearing D, and connecting-rod C. To the free end of the upper arm e' of the bent lever E is pivoted one end of a link e², whose other end is pivoted to a sleeve f, fast on the 85 needle-bar F, which, as shown in the drawings, is arranged obliquely. This needle-bar F reciprocates in guides a² a³ on the frame A and carries at its lower end the needle f', which is fixed thereto in any suitable or usual 90 manner.

G is the felling-needle bar, which, like the needle-bar F, is arranged obliquely and reciprocates in guides a⁴ a⁵ of the frame A. The needle-bar G carries a sleeve g analogous 95 to the sleeve f, to which is pivoted at g' one end of a connecting-rod g², the other end of which is pivoted to the free end of the lever-arm e³ of the lever E. At the lower end the needle-bar G carries the felling-needle g³, 100 which is secured thereto in any suitable or usual manner.

f^2 is the thread for the needle f' , and g^4 is the thread for the needle g^3 . These threads pass over suitable tension devices and through guiding-eyes, as shown, which do not form any 5 part of the invention, as they may be of any known construction and arrangement and need, therefore, not be described in detail.

h and h' indicate, respectively, a looper operating with the needle f' and a looper 10 operating with the felling-needle g^3 . These two loopers are mounted on a support or frame H , on which they oscillate lengthwise of the bed-plate or in planes at right angles to the planes of reciprocation of the needle-bars, 15 but in the opposite direction to each other about the rockers h^2 and h^3 , respectively. The frame H is suitably journaled in fixed bearings $A' A^2 A^3$ in such a manner as to be capable of oscillation in a direction crosswise 20 of the bed-plate under the action of an eccentric b^2 , which is mounted on the driving-shaft B and operates in a fork h^4 on the looper-support H , which is secured to suitable spindles S and S' for the purpose, as clearly shown 25 in Figs. 1 and 3. The longitudinal oscillatory movement on their rockers h^2 and h^3 is imparted to the loopers h and h' , respectively, by means of connecting-rods h^5 and h^6 , which are jointed at one of their ends to the tails of 30 the respective loopers h and h' , while the other ends are jointed by means of ball-and-socket or spherical joints $h^7 h^8$ to a common stud or pin i , which is journaled in the lower end of a lever I , keyed on the pivot stud or 35 pin e of lever E .

J is a presser-foot of any ordinary or suitable construction; but its foot-plate j is formed, as shown in the drawings, in a special manner and is provided on its under side 40 in the transverse direction with a projecting ridge j' in the form of a V , coöoperating with a transverse groove or recess a^6 of corresponding shape in cross-section formed in the work-plate a' . This arrangement has for its object, as will be readily understood by reference to Fig. 4, facilitating the folding of the knitted fabric or other material into the desired shape. Immediately behind the needle g^3 the plate j of the presser-foot is recessed 45 or cut out, as shown at j^2 , in order to allow, as will be explained later on, the cut edge of the knitted fabric to move nearer to the place where the needle g^3 in felling is entering the thickness of the fold of the top layer of such 50 fabric. In other words, the plate j of the presser-foot is made substantially in the form of an L in plan, Fig. 5, and from the rear end of the ridge j' projects a spur or lip j^4 in front of and across the slot j^3 to properly guide 55 the felling-needle.

Any suitable feed device may be used, and it may in shape correspond with the groove a^6 in the work-plate, or a feed mechanism of the wheel or other type may be used and operated in the usual or any well-known manner, such feeding device being omitted from the drawings to avoid complicating the same.

Immediately in front of the place where the sewing-needle f' is stitching there is arranged a knife K , Fig. 5, of the usual or other suitable construction, which cuts the knitted material at the desired place and which may be operated by any suitable or known means. 70

In Fig. 4 I have shown a sleeve k , adjustably secured by means of a set-screw k' to 75 the feller-needle bar G , said sleeve having a flat surface k^2 , forming a bearing for and to which is secured the knife K by means of screws k^3 , said knife working in an aperture $a^{\prime\prime\prime}$ in the work-plate a , Figs. 4 and 5. 80

Referring to Fig. 4, L and M indicate, respectively, the upper and lower layers of a knitted fabric. At the place N where, as will be hereinafter seen, the felling-needle g^3 enters the thickness of the upper layer L there is arranged a small guard-plate O , designed to prevent the needle g^3 from entering also the lower layer of the knitted fabric M and in a measure regulate the depth of penetration 85 of said needle into and through the upper layer. This guard-plate is particularly necessary in the case of thin materials, but in the case of very thick materials it may be dispensed with if desired. The said plate O is fixed to or formed on the end of a small arm 90 o , that is secured to the work-plate a' in an adjustable manner by means of a clamping-screw o' , working in a slot o^3 of the arm o , 95 Fig. 5.

The mode of operation of this machine is 100 as follows: In Fig. 1 the parts are shown at the end of the upward stroke—that is to say, at the moment when the two needles have moved out of the material. In Fig. 3 the parts are shown at the end of their downstroke—that is to say, at the moment when the driving-shaft B has described half a revolution, starting from the position shown in Fig. 1. The two needles have completely entered the material to form the stitches. 110 Both needles $f' g^3$ sew in the usual manner with chain-stitch, either with one or two threads, the two thicknesses or layers of the material, into which the needle f' enters at P and the needle g^3 at N , Fig. 4. I will therefore not dilate upon their action nor upon the manner in which the stitch is formed, because these are matters that are well known. I will also not dilate any further upon the action of the knife K , which cuts 120 the two thicknesses of the material in advance of the place where the needle f' is stitching said material in the well-known manner. In its downstroke the needle g^3 pierces first through the thickness of the top 125 layer L of the two layers of material at the point N , (the plate O preventing it from penetrating into the lower layer M at that point.) Then it passes through both layers L and M quite close to their cut edges and by tightening the stitch fells the two edges 130 of the material outside the stitching P upon the upper layer L , as is clearly shown in Fig. 7, in which Q indicates the felled seam.

When the article has been removed from the machine and has been unfolded, the stitch has the appearance shown in Fig. 8 without any apparent holes or stitching showing on the right side, while in the usual manner of sewing cut hosiery, Fig. 6^a, the felling-stitch *q* shows on the right side.

In cases where it is desired to produce only a simple felled flatseam instead of the French felled flat seam, as hereinabove described, the sewing-needle *f*³ is dispensed with, and, if desired, the shape of the presser-foot, the work-plate, and the feeding-claw may be modified, so as to produce a fold of less depth in the material, the sewing being effected with the needle *g*³, which will produce the simple felled seam shown in Fig. 9, as will be readily understood.

It will be understood that I do not limit myself in the carrying out of my invention to any particular arrangement of knife or of feeding device and that I may produce sewing in simple chain-stitch or in double chain-stitch or in any other kind of well-known stitch.

Having thus described my invention, what I claim as new therein, and desire to secure by Letters Patent, is—

1. In a sewing-machine, the combination with the bed-plate, the overhanging arm, a needle-bar carrying an eye-pointed needle and reciprocating in bearings in said arm in a plane oblique to said bed-plate, and a looper below the bed-plate coöoperating with the needle to form the stitch; of means connected with said bed-plate for presenting two layers of fabric to the needle to cause the same to sew the upper layer to both said layers along a line more or less distant from their edges, for the purpose set forth.

2. In a sewing-machine, the combination with the stitch-forming appliances comprising two needle-bars reciprocating at an angle to each other; of means for presenting two layers of fabric to the needles so as to cause one of them to sew together both layers to form a seam parallel with their free edges, and so as to cause the other needle to sew the upper layer along a similar line on one side of the seam formed by the first needle to both layers on the opposite side thereof, for the purpose set forth.

3. In a sewing-machine, the combination with the stitch-forming appliances comprising two needle-bars reciprocating at an angle to each other; of means for presenting two layers of fabric to the needles so as to cause one of them to sew together both layers to form a seam parallel with their free edges, and so as to cause the other needle to pass through the upper layer on one side of the aforesaid seam and between the upper and lower surfaces of said upper layer and sew the same to both layers on the opposite side of such seam, for the purpose set forth.

4. In a sewing-machine, the combination with the stitch-forming appliances, compris-

ing two needle-bars reciprocating at an angle to each other, and a work-plate having a recess or throat V-shaped in cross-section; of means for holding, during the stitch-forming operation, two layers of fabric in said recess so as to conform to the angularity thereof and so as to cause one of the needles to sew both layers together along a line parallel with the apex of the angle of said recess and so as to cause the other needle to sew the upper layer, on one side of the seam formed by the first needle, to both layers on the opposite side of said seam, for the purpose set forth.

5. In a sewing-machine, the combination with the stitch-forming appliances comprising two needle-bars reciprocating at an angle to each other, and a work-plate having a recess or throat V-shaped in cross-section; of a presser-foot provided with a ridge or projection corresponding in shape to that of the recess in said work-plate for holding, during the stitching operation, two layers of fabric so as to conform to the angularity of said recess and so as to cause one of the needles to sew the layers of fabric together along a line parallel with the apex of the angle of the aforesaid recess and so as to cause the other needle to pass through the upper layer on one side of the seam formed by the first needle, and sew said upper layer to both layers on the opposite side of said seam, for the purpose set forth.

6. In a sewing-machine, the combination with the stitch-forming appliances, comprising two needle-bars reciprocating at an angle to each other, and means for presenting two layers of fabric to the needles so as to cause one of them to sew both layers together along a line parallel with their free edges and to cause the other needle to sew the upper layer on one side of the seam formed by the first needle to both layers on the opposite side thereof along their free edges, and a reciprocating knife for cutting the said free edges outside of and along the edge seam, for the purpose set forth.

7. In a sewing-machine, the combination with stitch-forming appliances comprising two needle-bars having motion in bearings at an angle to each other, and mechanism for reciprocating the same, comprising a rotating shaft, the bent lever *E*, a connection between the latter and said shaft organized to impart an oscillating motion to the lever, the connecting-link *e*² connecting the arm *e*¹ of said lever *E* with one of the needle-bars, and the connecting-rod *g*² connecting the other arm *e*³ of the lever with the other needle-bar; of means for presenting two layers of fabric to the needles so as to cause one of them to sew both layers together along a line parallel with their free edges, and so as to cause the other needle to sew the upper layer on one side of the seam formed by the first needle to both layers on the opposite side of said seam along their free edges, for the purpose set forth.

8. In a sewing-machine, the combination

with the stitch-forming appliances, comprising two needle-bars arranged at an angle to each other, and an oscillating looper for each needle-bar, coöperating with the needle thereof to form the stitch; of a rocking shaft, mechanism operated thereby for reciprocating the needle-bars and for oscillating the loopers, and means for presenting two layers of fabric to the needles so as to cause one of them to sew both layers together on a line parallel with their free edges, and so as to cause the other needle to sew the upper layer on one side of the seam formed by the first needle to both layers on the opposite side of said seam along their free edges, for the purpose set forth.

9. In a sewing-machine, the combination with two needle-bars arranged at an angle to each other, a looper for each needle-bar coöperating with the needle thereof to form the stitch, and a support common to both loopers and on which support said loopers have oscillating motion; of a rotating shaft, a rock-shaft, mechanism operated by the rotating shaft to rock said rock-shaft, a radial arm on the last-named shaft, and connecting-rods connecting the tails of the loopers with said radial arm, for the purpose set forth.

10. In a sewing-machine, the combination with a driving-shaft, two needle-bars arranged at an angle to each other, a looper for each needle-bar coöperating with the needle thereof to form the stitch, a support common to both loopers, mounted to rock in bearings parallel with the driving-shaft, said loopers mounted on said support, to oscillate in bearings at right angles to said shaft; of mechanism operated by the last-named shaft for rocking the looper-support, oscillating the loopers, and reciprocating the needle-bars, for the purpose set forth.

11. The combination with the needle-bars F and G, the lever E and connections between the arms of said lever and said needle-bars respectively, the stud or spindle e on which said lever is secured, the radial arm I fast on said spindle, the shaft B, the eccentrics b' b² thereon, the ball-bearing D secured to lever E, and the connecting-rod C; of the looper-support H journaled in fixed bearings and provided with a bearing h⁴ for the eccentric b², the loopers h, h', secured to and having rocking motion on support H, and the connecting-rods h⁵ h⁶ connected with the radial arm I and with the heels or tails of the loopers h h' respectively, substantially as and for the purpose set forth.

12. In a sewing-machine, the combination with the bed-plate and the work-plate a' having the angular recess a⁶; of two needle-bars reciprocating at an angle to each other, one of said needle-bars arranged to pass through the work-plate at the apex of the angle formed by the aforesaid recess, the other needle-bar arranged to pass close above the vertical side and through the opposite inclined side of said

recess, and two oscillating loopers below the bed-plate and coöperating respectively with the needles carried by the needle-bars to form the stitch; of a single driving-shaft revoluble in bearings below said bed-plate, and mechanism operated by said shaft for reciprocating the needle-bars and for oscillating the loopers, for the purpose set forth.

13. In a sewing-machine, the combination with the bed-plate and the work-plate a' having the angular recess a⁶; of two needle-bars reciprocating at an angle to each other, one of said needle-bars arranged to pass through the work-plate at the apex of the angle formed by the aforesaid recess, the other needle-bar arranged to pass close above the vertical side and through the opposite inclined side of said recess, a presser-foot for holding the two layers of fabric along their free edges in, and so as to conform to said angular recess, and two oscillating loopers below the bed-plate and coöperating respectively with the needles carried by the needle-bars to form the stitch; of a single driving-shaft revoluble in bearings below said bed-plate, and mechanism operated by said shaft for reciprocating the needle-bars and for oscillating the loopers, for the purpose set forth.

14. In a sewing-machine, the combination with stitch-forming appliances comprising two needle-bars reciprocating at an angle to each other, and means for presenting two layers of fabric to the needles so as to cause one of said needles to sew both layers together and so as to cause the other needle to sew the upper layer on one side of the seam formed by the first needle to both layers on the opposite side thereof; of means coöperating with the last-named needle for regulating its depth of penetration into and through the upper one of the two layers of fabric, for the purpose set forth.

15. In a sewing-machine such as described, the combination with the work-plate a provided with the angular recess a⁶ and stitch-forming appliances comprising the obliquely-reciprocating needle-bar G and its needle; of the guard-plate O, substantially as and for the purpose set forth.

16. In a sewing-machine such as described, the combination with the work-plate a provided with the angular recess a⁶ and stitch-forming appliances comprising the obliquely-reciprocating needle-bar G and its needle; of the adjustable arm o provided at its free end with the guard-plate O lying below the line of reciprocations of the needle, substantially as and for the purpose set forth.

In witness whereof I have hereunto set my hand, this 5th day of December, 1898, in the presence of two subscribing witnesses.

STEPHEN ANDRÉ BRANDON.
